UNITED STATES PATENT OFFICE.

LYMAN S. STEVENS, OF BALTIMORE, MARYLAND.

APPARATUS FOR PROPORTIONING THE CHARGE OF FUEL AND AIR IN INTERNAL-COMBUSTION ENGINES.

1,269,757.

Specification of Letters Patent. Patented June 18, 1918.

Application filed May 25, 1915. Serial No. 30,310.

To all whom it may concern:

Be it known that I, LYMAN S. STEVENS, a citizen of the United States, residing at Baltimore city, in the State of Maryland, have invented a certain new and useful Apparatus for Proportioning the Charge of Fuel and Air in Internal-Combustion Engines, of which the following is a specification.

10 My invention relates to improvements in apparatus for proportioning the charge of fuel and air in internal combustion engines, and the object of my invention is the providing of means to measure the exact amount 15 of gas or carbureted air that is consumed in the cylinder of an internal combustion engine.

A further object of my invention is the providing of means of controlling the size 20 of the measure, measuring the amount of gas or carbureted air that is consumed or may be required to be regulated.

A further object of my invention is an improved regulator for regulating the size 25 of said measure, and,

A further object of my invention is the means of definitely proportioning the mixture of fuel and air in an internal combustion engine and of regulating said proportioning.

With the foregoing and other objects in view my invention consists of the novel construction, combination and arrangement of parts, as hereinafter specifically described 35 and illustrated in the accompanying drawing, wherein is shown the preferred embodiment of my invention, but it is to be understood that changes, variations and modifications can be resorted to which come within 40 the scope of the claims hereunto appended.

In the drawing of the herein described embodiment of my invention is shown a view 45 in elevation, partly in section, of my apparatus as applied to a double acting, two cycle, internal combustion engine, but I wish it understood that it will be just as effective if applied to a single acting, two cycle, four cycle, or other type of engine.

Similar numerals refer to similar parts 50 throughout the several views.

1 and 2 are the combustion cylinders. 3 and 4 are pistons operating within said cylinders and in the construction shown form a single piston. 5 is an expansion tank. 55 6 is a reducing valve. 7 is a pipe from the

supply. 8 is the conducting chamber which embraces pipes 9 and cylinder 10. 11 is a delivery pipe connecting expansion tank 5 to conducting chamber 8, the delivery from which is controlled by valve 12 operated by 60 cam 13 on oscillating disk 14, which disk 14 is operated from the main shaft 17 by eccentric 16 and rod 15.

In cylinder 10 is regulating piston 18 which is operated by screw 19 and hand 65 wheel 20, screw 19 and hand wheel 20 operating piston 18 out and in to vary the capacity of cylinder 10.

Pipes 9 connect to cylinders 1 and 2 through valves 21 and 22, which valves regulate the admission of fuel into the working cylinders from conducting chamber 8 and are operated and timed by cams 23 on disk 14. 24 is an air pump connected to cylinders 1 and 2 by air pipe 25. The admission of air 70 from pipe 25 is controlled by pistons 3 and 4 respectively, uncovering air admission ports at or near the end of their stroke, the air in air pipe 25 being under some pressure. 75 26 is an exhaust port for cylinder 1.

The operation of my invention is as follows:

The fuel which may consist of any expansive oxidizable substance, among which might be enumerated, hydrocarbon mixtures or evaporates and carbon monoxids, is admitted to expansion tank 5 and there maintained under substantially a constant pressure, by supply 7 and regulating valve 6.

Upon the opening of valve 12 conducting chamber 8 is filled with the fuel at the pressure of that of expansion tank 5, the capacity of conducting chamber 8 is varied by enlarging or decreasing the capacity of cylinder 10 on the working side of piston 18 by 90 the moving of said piston, thus the amount of fuel in conducting chamber 8, under a definite pressure is constant and predetermined and may be changed when desired.

Valves 12, 21 and 22 are so timed that 100 valve 12 is always closed when either of the others is open, and the other valves are so timed as to admit fuel from conducting chamber 8 into the respective cylinders which they each control at the desired time 105 of admission, relative to the pistons working therein.

Upon the opening of either valve 21 or 22, discharge takes place from conducting chamber 8 and the pressure drops therein 110

and becomes equalized with the pressure in the cylinder which is in communication therewith. I might remark here that the pressure in the expansion tank 5 is much in excess of the pressure in the cylinders at the time of admission through either valve 21 or 22.

For further information it may be desired to give a concrete example of one adjustment 10 and proportioning. Hydrocarbon gas may be admitted through supply pipe 7 at sixty pounds gage pressure and reduced by reducing valve 6 to thirty pounds gage pressure in expansion tank 5. And under the 15 condition that conducting chamber 8 have a relative cubical contents to cylinders 1 and 2 of one-sixth the size of each of said cylinders, fuel may enter said cylinders during the compression stroke at any point below 20 the expansion tank pressure, I have found between two and five pounds satisfactory.

Having thus described my invention, what I claim and desire to secure by Letters Patent is:

25 1. In an internal combustion engine, a working cylinder, means of admitting air to said cylinder from the atmosphere at atmospheric pressure, a source of gaseous fuel, a conducting chamber intermediate between 30 said source and said cylinder and means of controlling the entry and exit of gaseous fuel in said chamber in combination with means of varying the capacity of said chamber within the limits of its maximum or 35 minimum to predetermine a definite charge for said cylinder and means of maintaining said capacity during the discharge from said chamber.

2. In an internal combustion engine, a 40 working cylinder, means of admitting air to said cylinder from the atmosphere at atmospheric pressure, a source of gaseous fuel, a conducting chamber intermediate between said source and said cylinder and means of 45 controlling the entry and exit of gaseous fuel in said chamber in combination with means of varying the capacity of said chamber, consisting of a chamber provided with means of changing the volume thereof within 50 in the limits of its maximum or minimum to predetermine a definite charge for said cylinder and means of maintaining said capacity during the discharge from said chamber.

55 3. In an internal combustion engine, a working cylinder, means of admitting air to said cylinder from the atmosphere at atmospheric pressure, a source of gaseous fuel, a conducting chamber intermediate between 60 said source and said cylinder and means of controlling the entry and exit of gaseous fuel in said chamber in combination with means of varying the capacity of said chamber, consisting of a chamber provided with 65 means of changing the volume thereof within

the limits of its maximum or minimum to predetermine a definite charge for said cylinder and means of maintaining said capacity during the discharge from said chamber and external means for making such 70 regulation.

4. In an internal combustion engine, a working cylinder, means of admitting air to said cylinder from the atmosphere at atmospheric pressure, means of admitting fuel to 75 said cylinder from a source of constant pressure consisting of an intermediate chamber provided with means of changing the capacity thereof to predetermine a definite charge for said cylinder, means of maintaining said 80 capacity during the discharge from said chamber and means of controlling the flow of fuel in and out of said chamber.

5. In an internal combustion engine, means of proportioning the admixture of 85 gaseous fuel and air, consisting of an adjustable gaseous fuel measure whereby a predetermined definite quantity of gaseous fuel is admitted to a given quantity of air to predetermine a definite charge for said 90 cylinder and means of maintaining said capacity during the discharge from said chamber consisting of a chamber provided with means of changing the volume thereof.

6. In an internal combustion engine in 95 combination, a plurality of working cylinders provided with means of admitting fuel from a common source to each of the said cylinders independently, means of controlling the discharge into said common source, 100 a space between said discharge means and said admission means provided with means of varying the capacity of the same within the limits of its maximum or minimum, and automatic means operating to close said 105 space to each of the cylinders or supply as the case may be.

7. In an internal combustion engine, a gaseous fuel expansion tank provided with means of maintaining a constant pressure 110 therein, a working cylinder, means of controlling the admission of fuel into said cylinder, a conducting chamber between said expansion tank and said admission means provided with means of varying the capacity 115 thereof, and means of admitting from said expansion tank into said conducting chamber and closing the same when said cylinder admission means permits admission from said conducting chamber into said cylinder. 120

8. In an internal combustion engine, a gaseous fuel expansion tank provided with means of maintaining a constant pressure 125 therein, a working cylinder means of controlling the admission of fuel to said cylinder, a conducting chamber between said expansion tank and said admission means provided with means of varying the capacity thereof, consisting of a movable wall thereof and means of operating said wall from with 130

out to change the volume thereof, and means of admission from said expansion tank into said conducting chamber and closing the same when said cylinder admission 5 means permits admission from said conducting chamber into said cylinder.

9. In an internal combustion engine in combination a plurality of working cylinders provided with means of admitting fuel 10 from a common source to each of the said cylinders independently, means of controlling the discharge into said common source, a space between said discharge means and said admission means provided with means 15 of varying the same, and automatic means operating to maintain said space closed to each of the cylinders or supply as the case may be, and a gaseous fuel expansion tank provided with means of maintaining a con- 20 stant pressure therein in communication with said space and controlled by said admission means.

10. In an internal combustion engine, a working cylinder, means of admitting air to 25 said cylinder from the atmosphere at atmospheric pressure, a source of gaseous fuel, a conducting chamber intermediate between said source and said cylinder and means of controlling the entry and exit of gaseous 30 fuel in said chamber in combination with means of varying the capacity of said chamber to predetermine a definite charge for said cylinder and means of maintaining said capacity during the discharge from said chamber. 35

11. In an internal combustion engine, a working cylinder, a source of gaseous fuel supply, a conducting chamber intermediate 40 between said source and said cylinder and means of controlling the entry and exit of gaseous fuel in said chamber in combination with means of varying the capacity of said chamber within the limits of its maximum or minimum to predetermine a definite 45 charge for said cylinder and means of maintaining said capacity during the discharge from said chamber.

12. In an internal combustion engine, a working cylinder, a relatively fixed air supply, a source of gaseous fuel, a conducting 50 chamber intermediate between said source and said cylinder and means of controlling the entry and exit of gaseous fuel in said chamber in combination with means of varying the capacity of said chamber, consisting of a chamber provided with means of changing the volume thereof. 55

13. In an internal combustion engine, a working cylinder, a source of gaseous fuel, a conducting chamber intermediate between 60 said source and said cylinder and means of controlling the entry and exit of gaseous fuel in said chamber in combination with means of varying the capacity of said chamber, consisting of a chamber provided with 65 means of changing the volume thereof with- in the limits of its maximum or minimum.

14. In an internal combustion engine, a working cylinder, a relatively fixed air supply, a source of gaseous fuel, a conducting 70 chamber intermediate between said source and said cylinder and means of controlling the entry and exit of gaseous fuel in said chamber in combination with means of varying the capacity of said cylinder, con- 75 sisting of a chamber provided with means of changing the volume thereof and external means for making such regulation.

15. In an internal combustion engine, a working cylinder, a source of gaseous fuel, a 80 conducting chamber intermediate between said source and said cylinder and means of controlling the entry and exit of gaseous fuel in said chamber in combination with means of varying the capacity of said cylinder, consisting of a chamber provided with 85 means of changing the volume thereof with- in the limits of its maximum or minimum and external means for making such regulation.
